CLAIM

The ornamental design for a lid for a container, as shown and described.

DESCRIPTION

FIG. 1 is a top perspective view of a lid for a container when the lid is closed;

FIG. 2 is a top perspective view thereof when the lid is open;

FIG. 3 is a top plan view thereof when the lid is open;

FIG. 4 is a front elevational view thereof when the lid is open;

FIG. 5 is a side elevational view thereof when the lid is open;

FIG. 6 is a rear elevational view thereof when the lid is open;

FIG. 7 is a bottom plan view thereof when the lid is closed, the labeling and logos forming no part of the design; and,

FIG. 8 is a bottom perspective view thereof when the lid is closed, the labeling and logos forming no part of the design.
